WEB PERFORATING APPARATUS

Robert E. Pierce, Glendale, Mo., assignor to Bennis Bro. Bag Co., St. Louis, Mo., a corporation of Missouri

Application March 10, 1955, Serial No. 493,503

5 Claims. (Cl. 164—102)

This invention relates to web perforating apparatus, and more particularly to apparatus for punching holes at regularly spaced intervals in a continuous web along its length.

Among the several objects of the invention may be noted the provision of an improved apparatus for punching holes at regularly spaced intervals along the length of a continuous web of bag material such as polyethylene in order to provide ventilating openings in bags made from the material; the provision of apparatus of this class having a continuous-motion punching mechanism, as opposed to an intermittent-motion mechanism, which is operable at high speeds on a web of bag material which is travelling continuously at high speeds; and the provision of apparatus of this class which is of relatively simple construction and reliable in operation. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated,

Fig. 1 is an end elevation of a web perforating apparatus of this invention, parts being broken away in the center;

Fig. 2 is a left side elevation of Fig. 1;

Fig. 3 is an enlarged section taken on line 3—3 of Fig. 1;

Fig. 4 is an enlarged section taken on line 4—4 of Fig. 3;

Fig. 5 is a view similar to Fig. 3 showing a moved position of parts; and,

Fig. 6 is a diagrammatic view illustrating the motion of certain parts.

Corresponding reference characters indicate corresponding parts throughout the several views of the drawings.

Referring to the drawings, a web perforating apparatus of this invention is shown to comprise a frame generally designated 1 which constitutes a support for the various elements of the apparatus. The frame carries guide rolls 3 and 5 for guiding a web W of bag material, such as polyethylene tubing, for travel in a horizontal path from the roll 3 to the roll 5. As the web travels from the roll 3 to the roll 5, it passes between cooperative punch and die members 7 and 9 which function to punch holes in the web at regularly spaced intervals without impeding the web.

The punch 7 is actuated by a slider-crank mechanism comprising a bearing block 11 slidable transversely of the supporting frame 1 on a pair of upper horizontal guide bars 13. Block 11 has split ears 15 at its sides receiving the bars 13. It is adapted to be clamped at any desired position on the bars 13 by means of clamp screws 17 which extend through the ears 15. A transverse shaft 19 is rotary in the bearing block 11. This shaft has a gear 21 at one end and an eccentric 23 at the other. The

2

bearing block 11 has a downward radial extension 25. A tubular bracket or guide 27 is pivoted on the extension 25 as indicated at 29 for oscillation on an axis transverse to the axis of the guide 27 and transverse and parallel to the reach of the web between the guide rolls 3 and 5. A slider 31 constituted by a rod is mounted in the guide 27 for sliding movement transverse to the oscillatory axis of the guide 27. The punch 7 is fixed on one end (the lower and inner end) of the slider 31. The slider 31 has a strap 33 at its upper end on the eccentric 23.

The punch 7 comprises a tubular member 35 threaded on the lower end of the slider 31 and engaging a nut 37 threaded on the slider 31. The member 35 projects from the lower end of the slider 31 and its lower end is peened inward to provide a flange 39 bounding a circular opening 41. A hard steel ball 43 having a diameter somewhat larger than that of opening 41 is provided in the member 35. The ball 43 is biased to the position shown in Fig. 4 engaging the flange 39 and projecting from the lower end of the member 35 by a compression spring 45 in member 35 acting against a disk 47 which backs the ball 43.

The die 9 is actuated by a slider-crank mechanism comprising a bearing block 51 like block 11 which is slidable transversely of the supporting frame 1 on a pair of lower horizontal guide bars 53. Block 51 has split ears 55 at its sides receiving the bars 53. It is adapted to be clamped at any desired position on the bars 53 by means of clamp screws 57 which extend through the ears 55. A transverse shaft 59 is rotary in the bearing block 51. This shaft has a gear 61 at one end and an eccentric 63 at the other. The bearing block 51 has an upward radial extension 65. A tubular bracket or guide 67 is pivoted on the extension 65 as indicated at 69 for oscillation on an axis which is transverse to the axis of the guide 67 and which is transverse and parallel to the reach of the web between the guide rolls 3 and 5. A slider 71 constituted by a rod is mounted in the guide 67 for sliding movement transverse to the oscillatory axis of the guide 67. The die 9 is fixed on one end (the upper and inner end) of the slider 71. The slider 71 has a strap 73 at its lower end on the eccentric 63.

The die 9 comprises a tubular member 75 which is threaded on the upper end of the slider 71 and which engages a nut 77 threaded on the slider 71. Member 75 projects from the upper end of rod 71. Secured in the upper end of the member 75 is an annular hard steel seat 79 having an opening 81 of smaller diameter than the ball 43. Below the opening 81, the seat has an enlarged passage 83. Member 75 has a lateral opening 85. At 87 is indicated an upper transverse shaft journaled in bearings 89 mounted on the frame. A gear 91 is slidably keyed to the shaft 87 and meshes with the gear 21. Shaft 87 is driven by an electric motor 93 via gearing 95. It will be understood that the shaft 87 may be driven by other means. At 97 is indicated a lower transverse shaft journaled in bearings 99. A gear 101 is slidably keyed on the shaft 97 and meshes with the gear 61. Shaft 97 is driven from the shaft 87 via a vertical shaft 103 with bevel gear connections 105 between 87 and the upper end of shaft 103 and bevel gear connections 107 between the lower end of shaft 103 and the end of shaft 97.

Operation is as follows:

The bearing blocks 11 and 51 are clamped on the guide bars 13 and 53 in such position that the punch and die 7 and 9 are properly located transversely with respect to the web W. Gears 91 and 101 are adjusted on shafts 87 and 97 to mesh with gears 21 and 61 and fixed in position as by set screws. The eccentrics 23 and 63 are phased so that when the center of eccentric 23 is directly below the center of shaft 19, the center of eccentric

63 is directly above the center of shaft 59 (see Fig. 3). Shaft 19 and eccentric 23 rotate clockwise and shaft 59 and eccentric 63 rotate counterclockwise as viewed in Figs. 2, 3 and 5. The rotation of the eccentrics causes oscillation of the sliders 31 and 71 about horizontal transverse axes at 29 and 69. It also causes sliding movement of the sliders 31 and 71 in guides 27 and 67. The resultant of the oscillation and sliding movement is such that the ball 43 and the seat 79 move in the circular paths indicated at A and B in Fig. 6, which paths intersect at C. At such intersection, the ball presses the web into the opening 81 in the seat 79 and punches out a circular piece of the web (two circular pieces where the web is polyethylene tubing) against the edge of the seat 79 bounding the opening 81. The speed of the eccentrics is such that as the ball and the seat come together, they are travelling forward with the web at least approximately at the speed of the web. The pieces cut from the web are ultimately squeezed out of the opening 81 and fall through passage 83 into the member 75. Ultimately these pieces come out through the lateral opening 85.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

I claim:

1. Apparatus for perforating a continuously travelling web comprising a frame, means mounted on the frame for guiding the web for travel in a predetermined path, a pair of bearing blocks located on opposite sides of the path of the web mounted for transverse sliding adjustment relative to the web path on fixed guide means carried by the frame on opposite sides of the web path, a shaft rotary in each block on an axis transverse to the web path and movable with the block, a pair of drive shafts carried by the frame extending transversely with respect to the path of the web on opposite sides of said path, means for connecting said drive shafts and the first-mentioned shafts for driving the latter in various positions of adjustment of the blocks, a guide mounted on each block for oscillation on an axis transverse to the web path and movable with the block, a slider guided by each guide for sliding movement transverse to the oscillatory axis of the guide and movable with the block, the sliders having opposed inner ends provided with cooperating perforating members adapted upon engagement thereof to perforate the web, means connecting the outer ends of said sliders and said first-mentioned shafts for effecting rotation of the outer ends of the sliders around the axes of said first-mentioned shafts, means for positively driving one of said drive shafts, and means for driving the other drive shaft from said one drive shaft.

2. Apparatus as set forth in claim 1 wherein each of said fixed guide means comprises a pair of guide bars extending transversely across the frame, each of said bearing blocks being slidable on the respective pair of bars transversely with respect to the web path, and wherein in clamping means is provided for clamping the blocks to the bars at various transverse positions thereon.

3. Apparatus as set forth in claim 2 wherein the means connecting the outer end of each slider and the respective first-mentioned shaft comprises an eccentric on the shaft and a strap at the outer end of the slider on the eccentric.

4. Apparatus as set forth in claim 2 wherein each of said oscillatory guides is tubular and the sliders are slideable therein.

5. Apparatus for perforating a continuously travelling web comprising a frame, means mounted on the frame for guiding the web for travel in a predetermined path, a pair of bearing blocks located on opposite sides of the path of the web mounted for transverse sliding adjustment relative to the web path on fixed guide means carried by the frame on opposite sides of the web path, a shaft rotary in each block on an axis transverse to the web path and movable with the block, an eccentric and a gear on each of said shafts, a pair of drive shafts carried by the frame extending transversely with respect to the path of the web on opposite sides of said path, a gear slidably on and rotary with each of said drive shafts and meshing the gear on the respective one of the first-mentioned shafts, a tubular guide mounted on each block for oscillation on an axis transverse to the guide axis and to the web path and movable with the block, a slider guided by each guide for sliding movement therein transverse to the oscillatory axis of the guide and movable with the block, the sliders having opposed inner ends provided with cooperating perforating members adapted upon engagement thereof to perforate the web, a strap at the outer end of each of said sliders on a respective eccentric for effecting oscillation of each slider on the axis of its guide and inward and outward sliding movement of the slider in its guide, means for positively driving one of said drive shafts, and means for driving the other drive shaft from said one drive shaft.
